UNITED STATES PATENT OFFICE

2,494,184

ROCKING HORSE

Martin W. Linder, Alviso, Calif.

Application May 24, 1946, Serial No. 672,051

2 Claims. (Cl. 272—52)

1

The present invention relates to new and useful improvements in toys, and more particularly to the class of toys commonly known as rocking horses.

An important object of the present invention is to provide a toy of this character in which a platform is provided for the horse, together with means for swingably supporting the platform from uprights to provide for a forward and backward swinging movement of the horse.

Another object of the invention is to provide a toy of this character in which the parts may be collapsed into a compact form for convenient storage or shipping purposes.

A still further object is to provide a device of this character of simple and practical construction, which is neat and attractive in appearance, strong and durable, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view.

Figure 2 is a top plan view.

Figure 3 is a front elevational view.

Figure 4 is an enlarged perspective view of one of the hinged brackets for securing the horse in an upright position on the platform, and

Figure 5 is a fragmentary side elevational view showing the folding brace.

Referring now to the drawings in detail, wherein for the purpose of illustration I have disclosed a preferred embodiment of the invention, the numeral 5 designates a base for the toy which is of open frame construction and including a pair of longitudinal frame members 6 and a pair of transverse or end frame members 7 connected to the ends of the longitudinal frame members in any suitable manner, preferably for easily and quickly detaching the frame members from each other to provide a knockdown construction.

Corner posts 8 are secured at their lower ends at the corners of the frame 5 by means of screws or the like 9, whereby the posts may be swung downwardly against the inside of the longitudinal frame members 6 into a collapsed position. The posts are secured in an upright position by means of folding braces 10 pivoted at their ends to

2

the longitudinal frame members 6 and to the posts 8.

A platform 12 is provided at its under side adjacent each end with bearing brackets 13 in which the lower portion of U-shaped hangers 14 are rotatably received, the bight portion 15 of the hangers extending transversely under the platform and the arms 16 of the hangers extending upwardly in diverging relation at the sides of the platform and formed at their upper ends with horizontal trunnions 17 pivotally received in openings 18 at the upper portions of the posts 8. The arms 16 of the hangers are constructed of material possessing the necessary resiliency to spring the arms inwardly when inserting the trunnions 17 into position in the openings 18 and when removing the trunnions therefrom.

When detaching the hangers from the posts 8, the hangers may be swung into position under the platform 12 into a collapsed position.

As more clearly illustrated in Figure 2 of the drawings, the ends of the platform 12 are reduced in width, as indicated at 19, to provide shoulders 20 on the platform to function as stops 25 for engagement with the arms 16 of the hangers to limit the forward and backward swinging movement of the platform and thus prevent injury to a child using the toy.

An imitation toy horse 21 is constructed from a board or other flat material and is supported in an upright position on the platform 12 by means of brackets 22 and 23 secured to the upper surface of the platform and engaging the opposite sides of the board 21.

The bracket 22 includes a horizontal member 24 secured to the platform 12 and a vertical portion 25 secured to one side of the board 21 by a bolt and wing nut 26, the vertical arm 25 of the bracket being hinged to the horizontal arm 24 for vertical swinging movement by means of a conventional hinge structure 27.

The bracket 23 includes a horizontal arm 28 formed of hinge plates 29 and 30, the plate 29 being secured to the platform 12, while the plate 30 is free to swing vertically thereon. One end of the plate 30 is formed with a vertical arm 31 engaging the side of the board 21 opposite the vertical arm 25 of the bracket 22, the upper portion of the arm 31 being formed with a notch 32 adapted for releasable engagement with the bolt and wing nut 26.

The upper edge of the board 21 forming the imitation horse is provided with a saddle 33 and pegs 34 providing a hand grip for a child seated on the saddle.

It is believed the manner of constructing and assembling the toy will be readily understood from the foregoing, and when it is desired to ship or store the toy in a collapsed form, the bolts and wing nuts 26 are released, the vertical arm 31 of the bracket 23 swung downwardly and the horse 21 may then swing downwardly on the platform by means of the hinged bracket 22.

The trunnions 17 of the hangers 14 are sprung out of the openings in the posts 8 to fold under the platform and the posts 8 may also be folded on the inside of the frame member 6 by releasing the braces 10. If desired, the frame members 6 and 7 may also be disconnected from each other to store the frame in a knock-down condition.

It is believed that the details of construction, manner of use and advantages of the device will be readily understood from the foregoing without further detailed explanation.

It is to be understood, however, that even though I have herein shown and described a preferred embodiment of my invention, the same is susceptible of certain changes fully comprehended by the spirit of the invention as herein described, and the scope of the appended claims.

Having thus described the invention, what I claim is:

1. In a rocking horse, a horizontally-disposed base comprising a pair of longitudinal frame members, a transverse frame member detachably connected to each of the ends of said longitudinal frame members, an upright arranged at each corner of said base and having one end pivoted to the adjacent longitudinal frame member for movement from a horizontal position in alignment with said frame member to a position perpendicular to said frame member, a foldable brace contiguous to each corner of said base having one end pivoted to the longitudinal frame member adjacent thereto and having the other end pivoted to the upright adjacent thereto, a platform interposed between the longitudinal and transverse frame members, opposed hangers pivoted to said platform for swinging movement from a horizontal to a vertical position and detachably and suspendedly connected to the other ends of the adjacent uprights, a transversely-disposed bracket rigidly supported on the top of said platform, an arm pivotally connected to said bracket for swinging movement from a position horizontal with respect to said platform to a position vertical with respect to said platform, a second transversely-disposed bracket positioned on the top of said platform in spaced parallel relation with respect to said first-named bracket and rigidly supported on said platform, a second arm pivotally connected to said second-named bracket for swinging movement from a position horizontal with respect to said platform to a position vertical with respect to said platform, a toy horse provided with a seat portion positioned between the arms of said first and second-named brackets and having its sides in engagement with said arms when the latter have been swung to the position vertical with respect to said platform, and removable bolts extending through said arms and said toy horse for securing the toy horse in the vertical position.

in engagement with said portions when the latter have been swung to the position vertical with respect to said platform, and means extending through the portion of the first-named bracket, toy horse, and the portion of said second-named bracket for detachably securing the toy horse in vertical position.

2. In a rocking horse, a horizontally-disposed base comprising a pair of longitudinal frame members, a transverse frame member detachably connected to each of the ends of said longitudinal frame members, an upright arranged at each corner of said base and having one end pivoted to the adjacent longitudinal frame member for movement from a horizontal position in alignment with said frame member to a position perpendicular to said frame member, a foldable brace contiguous to each corner of said base having one end pivoted to the longitudinal frame member adjacent thereto and having the other end pivoted to the upright adjacent thereto, a platform interposed between the longitudinal and transverse frame members, opposed hangers pivoted to said platform for swinging movement from a horizontal to a vertical position and detachably and suspendedly connected to the other ends of the adjacent uprights, a transversely-disposed bracket rigidly supported on the top of said platform, an arm pivotally connected to said bracket for swinging movement from a position horizontal with respect to said platform to a position vertical with respect to said platform, a second transversely-disposed bracket positioned on the top of said platform in spaced parallel relation with respect to said first-named bracket and rigidly supported on said platform, a second arm pivotally connected to said second-named bracket for swinging movement from a position horizontal with respect to said platform to a position vertical with respect to said platform, a toy horse provided with a seat portion positioned between the arms of said first and second-named brackets and having its sides in engagement with said arms when the latter have been swung to the position vertical with respect to said platform, and removable bolts extending through said arms and said toy horse for securing the toy horse in the vertical position.
